UNITED STATES PATENT OFFICE.

EMIL REINER, OF GRATZ, AUSTRIA-HUNGARY, ASSIGNOR TO THE FIRM OF JOHANN PUCH, ERSTE STEIERMÄRKISCHE FAHRRAD-FABRIKS AKTIEN-GESELLSCHAFT, OF GRATZ, AUSTRIA-HUNGARY.

TYPE-WRITER.

1,097,046.

Specification of Letters Patent.

Patented May 19, 1914.

Application filed August 15, 1913. Serial No. 784,924.

To all whom it may concern:

Be it known that I, EMIL REINER, engineer, subject of the King of Hungary, residing at Gratz, in the Empire of Austria-Hungary, have invented certain new and useful Improvements in Type-Writers, of which the following is a specification, reference being had therein to the accompanying drawing.

10 As is well known the inking ribbon of typewriting machines is made to unwind from one spool upon the other by striking the operating keys, and it is necessary to provide means for reversing the winding movement when the ribbon has been completely unwound from one of the spools. In machines of the kind in which this reversing movement does not take place automatically, it must be produced by the alternate 15 opposite movements of a reversing member, and by releasing and readjusting fixing devices, and the necessity for attending to these operations, distracts the operator's attention from writing.

20 My device is characterized by the fact that the reversing movements are obtained from the reciprocation of a reversing lever which is alternately actuated by two crank pins of a resilient key, by the intermediary of two 25 members, rigidly connected with each other and with a trip arm arranged in their angle; the rigid system composed of the two members and the trip arm being rockably mounted on the reversing lever, within a limited 30 extent, and being directly actuated by the crank pins of said key which bear alternately against the free ends of the two members.

35 Another feature of the invention resides 40 in the fact that for the purpose of insuring the movement into its two end positions and retaining it therein, the reversing lever is provided upon its upper end with two converging striking surfaces, in each of which 45 there is a notch; a roller, or a knife edge, preferably mounted on the end of a resilient lever, acts against these striking surfaces.

The invention is fully illustrated in the accompanying drawing, in which:

50 Figure 1, shows the operating mechanism in vertical longitudinal section of the machine, parallel with the inking ribbon. Figs. 2 and 3 show the mechanism in two different positions. Fig. 4, shows the kinematic co-

operation of the constructional elements diagrammatically. Fig. 5, is a section on the line A—A, in Fig. 1 viewed from the right.

The inking ribbon *h* is caused to be unwound from the spool *t* and to be wound upon the other spool *s*; the alternating movement of the spools *t* and *s*, is obtained from a shaft *n*, adjustable in the direction of its length, and which, by means of the operating pawl *m*, actuated at each depression of a key, rotates, to the extent of one tooth, the ratchet wheel *o*, keyed upon the shaft *n*. Two bevel pinions 20, 21, are keyed upon this shaft *n*, and, by the longitudinal movement of the shaft *n*, these pinions are caused to mesh with the driving shaft *a*, of the spool *t*, or with the driving shaft *b* of the spool *s*. The longitudinal movement of the shaft *n* which is required for reversing the movement of the ribbon, is effected by the lever *q*, rockable upon the bolt *f*: the lower end of this lever *q* carries a claw *d*, which loosely engages upon the edge of a disk *j*, fixed on the shaft *n*.

The present invention has for its object to insure the reciprocatory movement of this operating lever *q*, by the actuation of a resilient, or spring operated key *p*, always taking place in the same direction, thereby shifting this lever with certainty into its end positions and securing it therein. With this object in view an anchor-like member *v*, is pivoted on the lower arm of the lever *q* at the point 1; (see Fig. 4). This member *v*, consists of two rigidly connected members 2 and 4, set at a certain angle one to the other, and rigidly connected with an arm 3, located in the space between the members 2 and 4, and carrying a trip weight *k*. Stop pins 5, 5, arranged upon the members 2, and 4, or upon the trip arm 3, limit the extent of oscillation of the entire system constituted by the rigidly connected parts 2, 3 and 4, relatively to the operating lever *q*. The free ends of the two members 2 and 4, have notched striking surfaces 6 and 8, against which the crank pins 7 and 9, of the spring operated key lever, act.

One of the positions of the system indicated by the Figs. 2, 3, 4, corresponding to the two operative positions of the lever *q*, is shown in solid lines and the second position, in broken lines. (See Fig. 4). In the position shown in solid lines (Figs. 1 and 4),

the crank pin 7, of the key *p* rotatable about the shaft 10, rests upon the surface 6 of the member 2; if the key *p* is depressed the pin 7 presses the member 2 downward toward the right and this part becoming operative in the direction indicated by the arrow 11, imparts a right hand movement to the pivot point 1, causing the lever *q* to oscillate in the direction indicated by the arrow 11. As the pin 7 remains in engagement with the surface 6 of the member 2, this rotation of the lever lasts until the end of the stroke of the key *p*, or until the lever *q* has reached the end position *q'* shown in broken lines diagrammatically, in Fig. 4. By this means however, the system 2, 3, 4, has been shifted beyond its middle position by the movement of its pivot point 1, to 1'. When the key lever *p* has been released it springs upward, and therefore also releases the system, 2, 3, 4, and the latter under the influence of the weighted trip arm 3, rocks into its lowest position, determined by the striking of the right hand stop pin 5, against the lever *q*. This position is represented in Fig. 3, and diagrammatically illustrated by the lines 2', 3', 4', in Fig. 4. By this rocking movement however, the striking surface 8, of the member 4, has come beneath the second crank pin 9 of the key lever *p*, so that when the key is again depressed the lever *q* is automatically returned to the position shown in Fig. 1, that is to say, the position diagrammatically represented in solid lines, Fig. 4, by the operation of the right hand member 4. From this it will be noted that by the successive depressions of the key *p*, the operating lever is first oscillated to the right, and then to the left, thereby reversing the movements of the inking ribbon. In order that the operating lever, may be conducted to its end position, with certainty, and retained in this position, upon its upper end, two converging striking surfaces 12, 12, ending in notches 13, 13, are provided, and against these surfaces a weighted roller *y*, preferably mounted on the end of a resilient arm *w*, operates so that the action of the roller

pressure ends only when the roller has entered one of the notches 13.

50

In order to assist the action of the trip weight 3, two converging striking surfaces 14, 14, are provided at the end of the trip arm 3; against these surfaces a wedge shaped knife edge *u*, on the end of a spring controlled lever *z*, operates, and owing to the movement of the key lever this knife edge *u* is carried beyond the apex, and then exerts a tangential pressure upon the striking surfaces over which it has traveled, thus assisting the turning movement of the trip weight and thereby insuring the trip movement, even if the carrier is in bad condition.

55

60

65

Having now described my invention and the manner in which it is to be used, what I claim is,—

1. In a type writing machine having ribbon wheels and mechanism to wind the ribbon alternately from one wheel to the other, a transverse operating shaft, a weighted arm, two rigidly connected members having recessed upper faces fixed on said weighted arm a spring controlled key having pins thereon to engage said weighted arm and depress said rigid members, and means on said arm to engage a disk on the inner end of said transverse shaft.

70

2. In a typewriting machine a horizontal shaft suitably journaled, a spring controlled key having outstanding pins thereon, a rockable member having recessed terminal surfaces depressed alternately by one or the other of said pins causing said member to oscillate, a spring controlled arm, a roller at the end of said arm, inclined surfaces on the upper end of said lever, traversed by said roller, and a claw on the lower end of said rocking member loosely engaging a disk on said horizontal shaft, as described.
